(57) **CLAIM**

The ornamental design for a retractable musician's cord, as shown and described.

DESCRIPTION

FIG. 1 is a perspective view of a retractable musicians cord according to the invention wherein the environmental elements of the male and female connection ends of the cord, the ball stop and retaining clip used to keep the male end from being retracted into the housing, the rubberized texturing on the handle, and the three rubber feet are shown in phantom lines.

FIG. 2 is a left side elevational view of the FIG. 1 device wherein the male end of the cord is shown straightened relative to the FIG. 1 view.

FIG. 3 is a right side elevational view of the device as depicted in FIG. 2.

FIG. 4 is an end elevational view of the device as seen from the left of FIG. 2;

FIG. 5 is an end elevational view a of the device as seen from the right of FIG. 2;

FIG. 6 is a top plan view of the device as depicted in FIG. 2; and,

FIG. 7 is a bottom plan view of the device as depicted in FIG. 2.

The broken line elements (described in FIG. 1) shown throughout the views are illustrating environment only and form no part of the claimed design.
